UNITED STATES PATENT OFFICE.

ALFRED J. FLAUDER, OF BRIDGEPORT, CONNECTICUT, ASSIGNOR TO THE WEIDLICH BROS. MFG. CO., OF BRIDGEPORT, CONNECTICUT, A CORPORATION OF CONNECTICUT.

DESIGN FOR A TRAY.

Application filed December 24, 1924. Serial No. 11,782. Term of patent 3½ years.

To all whom it may concern:

Be it known that I, ALFRED J. FLAUDER, a citizen of the United States, and a resident of Bridgeport, in the county of Fairfield and State of Connecticut, have invented a new, original, and ornamental Design for Tray, of which the following is a specification, reference being had to the accompanying drawing, forming a part thereof, and wherein is shown a perspective view of a tray embodying the design.

I claim:

The ornamental design for a tray substantially as shown.

Signed at Bridgeport, in the county of Fairfield and State of Connecticut, this 19th day of December, A. D. 1924.

ALFRED J. FLAUDER. [L. S.]
